(57) **CLAIM**

The ornamental design for a ceramic milling machine, as shown and described.

DESCRIPTION

FIG. 1 is a front perspective view of a ceramic milling machine showing my new design.

FIG. 2 is a front elevational view thereof.

FIG. 3 is a left side elevational view thereof.

FIG. 4 is a right side elevational view thereof.

FIG. 5 is a top plan view thereof.

FIG. 6 is a front perspective view of the ceramic milling machine of FIG. 1, with a receptacle in an open position; and, FIG. 7 is a front perspective view of the ceramic milling machine of FIG. 6, with the receptacle removed.

Any broken lines are for illustrative purposes only and forms no part of the claimed design.

The broken lines in the drawings depict unclaimed environmental subject matter.
